J. EATON

ELECTROMAGNETICALLY CONTROLLED DEVICE

Filed Sept. 29, 1921

Inventor:
John Eaton,
by *Alfred Darr*
His Attorney.

UNITED STATES PATENT OFFICE.

JOHN EATON, OF SCHENECTADY, NEW YORK, ASSIGNEE TO GENERAL ELECTRIC COMPANY, A CORPORATION OF NEW YORK.

ELECTROMAGNETICALLY-CONTROLLED DEVICE.

Application filed September 29, 1921. Serial No. 504,051.

To all whom it may concern:

Be it known that I, JOHN EATON, a subject of the King of Great Britain, residing at Schenectady, in the county of Schenectady, State of New York, have invented 5 certain new and useful Improvements in Electromagnetically-Controlled Devices, of which the following is a specification.

One of the objects of the invention is to 10 provide an electromagnetically controlled device in which a controlled member biased to one position is magnetically held in a second position when the energization of the electromagnet is above a predetermined 15 minimum value, and arranged so that when the energization of the electromagnet is above a predetermined maximum value, the controlled member is directly operated away from the second position.

20 A further object of the invention is to provide an electromagnetically controlled switch in which a switch member is magnetically held in the closed position against its bias to the open position when the energization of the switch electromagnet is above a predetermined value and which is magnetically and directly operated to the open position when the energization of the electromagnet is above a predetermined 25 maximum value.

30 A further object of the invention is to provide a circuit controller which combines the feature of manual control and also the feature of automatic control to protect a controlled circuit from abnormal conditions, such, for example, as an overload or a failure of voltage, although in certain of its aspects, the invention is not necessarily limited to a manually controlled switch.

40 In carrying the invention into effect in one form as applied to an electric switch, means is provided for closing and opening the controlled circuit at the will of the operator or in response to any predetermined 45 condition. The said means may take the form of open and close or start and stop push buttons, although the invention is not necessarily limited to a push button operated switch, nor are certain of the features 50 of the invention limited in their use to a manually operated switch. A switch member is under the control of the said means and also under the control of an electromagnet which may have a single winding energized 55 responsively to the current through

the switch. The electromagnet is provided with magnetic movable means under the control of the magnet winding or windings, and the arrangement is such that the switch member is magnetically held thereby in an 60 operated position as long as the conditions in the controlled circuit are normal or until the said manual means is operated to return the switch to its original position. In case an abnormal circuit condition occurs, such, 65 for example, as a failure of voltage, the magnetic holding effect on the magnetic movable means of the electromagnet is reduced and the switch member is returned from the closed circuit position to the open 70 position in accordance with its bias; or in case there is an overload in the controlled circuit, the magnetic movable means is magnetically operated to open the switch and permit the switch member to automatically 75 return to the open position.

For a better understanding of the invention, reference is had to the accompanying drawing in which I have shown one form 80 of an improved switch in accordance with the invention for the purpose of illustrating the principles of the invention. Referring to the drawing, Fig. 1 is a side view of my improved switch in the open position; Fig. 2 is an end view of the same; Fig. 3 is a detail showing the parts of the switch in the closed circuit position; Fig. 4 is a detail showing the positions of the parts when the switch is either manually operated to the open position or automatically operated to 85 the open position in response to an overload in the controlled circuit. It will be understood from the following description that the parts of the switch are automatically returned from their respective positions 90 shown in Fig. 4 to their respective positions shown in Fig. 1 when the manual opening means is released or after the circuit has been opened automatically in response to an overload. Fig. 5 is a simplified motor control diagram in which my switch is shown conventionally; and Fig. 6 is a detail showing a top view of the magnetic movable member of the controlling electromagnet and the movable switch member secured thereto. 95

100 Referring to the drawings, the switch member 10 is adapted to make engagement with the stationary contact 11 to complete an electric circuit through the contacts and to also energize the coil 12 of the electromag- 110

net for the switch. The movable contact 10 is carried by the movable magnetic member of the electromagnet. In the present form of my invention, this magnetic member comprises two relatively movable armatures 13 and 14, the switch member 10 being mechanically connected to the armature 13 so as to be directly operated thereby. These two armatures 13 and 14 are pivotally connected to each other at 15, and the armature 14 is pivotally connected with the frame 16 at 17. The two armatures are biased to their respective positions as shown in Fig. 1 by the spring 18, and the arrangement is such that the switch may be manually closed as shown in Fig. 3 by the operation of the close or start push button 19. After having been closed in this manner, the arrangement is such that the switch will be magnetically held in the closed position as long as the current in the winding 12 is above a predetermined minimum value, and in case the current in the winding rises to a predetermined maximum value, the armature 13 is attracted thereby directly opening the switch and permitting the armatures and the switch member 10 to return to their respective positions shown in Fig. 1. In case the start button 19 is held closed and the current in the magnet winding is above the predetermined maximum value, the armature 13 will be attracted to open the switch. When the switch is thus opened it is permitted to automatically reclose. This feature may be used to advantage in starting an electric motor, the start button being held closed until the motor accelerates to such a value that the automatic opening of the switch would not occur during starting and the start button may then be released so as to provide for automatic voltage failure and overload protection.

With the switch magnetically held closed as shown in Fig. 3, depressing the push button 20 causes the switch member 10 to break engagement with the stationary contact 11 and thereby open the contact. Releasing the pressure on the push button 20 will permit the armatures and switch member to return to their respective positions as shown in Fig. 1.

It will be observed that the magnetic movable member, comprising the armatures 13 and 14, is disposed with respect to the magnetic structure of the switch so as to provide an air gap indicated at 21 which may be termed the "closing air gap", and another air gap 22 in series with the air gap 21 which may be termed the "opening air gap". These two air gaps are in the flux path of the electromagnet and the air gap 21 is closed when the switch is closed and magnetically held closed, and the air gap 22 is open while the switch is closed. The switch is automatically opened when the current in

the winding 12 rises above a predetermined maximum value by the magnetic pull across the air gap 22 against the action of the spring 18, which provides a resilient connection between the armatures 13 and 14 70 whereby these armatures are normally biased to their respective open positions as shown in Fig. 1.

The operation of my invention as thus constructed and arranged may be readily understood from a consideration of Fig. 3 in connection with Figs. 1, 3 and 4. In order to close the switch and thereby energize the electric motor 23, the start push button 19 will be depressed, thereby moving the armature 14 against the action of the spring 18 to the position shown in Fig. 3. The pivotal connection between these two armatures is located at such a place that the lowering of the armature 14 also lowers the right hand end of the armature 13, thereby carrying the switch member 10 into engagement with the stationary contact 11, as shown in Fig. 3. When the switch contacts are thus closed, the winding 12 of the switch is energized through the switch contacts and the motor 23 is connected across the source of supply 24. The armature 14 will be magnetically held in the closed position by the attraction of the electromagnet for the armature 14. In case at any time the voltage of the supply circuit 24 should either fail or in some other manner the current through the winding be reduced to a predetermined minimum value, the armature 14 is automatically released to return to its normally open position, thereby simultaneously raising the right hand end of the armature 13 and the switch member 10. The circuit for the electric motor is thereby interrupted and will not be completed until the operator does a definite act, namely depressing the push button 19.

With the switch in the closed position, in case at any time the current taken by the electric motor should exceed a predetermined maximum value, the left hand end of the armature 13 will be attracted to close the air gap 22 and thereby directly raise the right hand end of the switch member 10 out of engagement with the stationary contact 11. The circuit through the winding 12 being thereupon interrupted, the armatures and switch member are returned to their respective positions as shown in Fig. 1 by the action of the spring 18. If the operator desires at any time to manually open the switch, he may do so by depressing the push button 20, thereby causing the armatures and switch member to assume their respective positions shown in Fig. 4. Releasing the push button 20 will permit the armatures and switch member to return to their respective positions shown in Fig. 1. If both the start and stop push buttons are de-

pressed while the switch is in the open position, the switch member 10 will not be permitted to make engagement with the stationary contact 11, the arrangement being 5 such that the switch member will merely be moved about the pivot 15 without making engagement with the contact 11.

I would have it understood that while the invention is useful as a combined manual 10 and automatic overload and voltage failure protective switch, the invention is not necessarily limited to a manually operated switch, since the switch may be closed in any suitable manner, as for instance, electromagnetically closed in response to any predetermined condition, as will be well understood by those skilled in the art.

In accordance with the provisions of the patent statutes, I have described the principle of operation of my invention, together 20 with the apparatus which I now consider to represent the best embodiment thereof, but I desire to have it understood that the apparatus shown is only illustrative and 25 that the invention may be carried out by other means.

What I claim as new and desire to secure by Letters Patent of the United States, is:

1. An electromagnetically controlled device comprising a movable controlled member, a controlling electromagnet therefor having a magnetic structure, a magnetic movable member connected to the said controlled member and disposed with respect 30 to the said magnetic structure to provide an air gap which is normally open, a second magnetic movable member cooperating with the said first magnetic movable member and disposed with respect to the said magnetic structure to provide a second air gap which is open when the controlled member is in a second position, and a resilient connection between the said magnetic movable members, whereby the controlled member is 35 moved to the second position by the operation of the first of said magnetic members to close the first said air gap and magnetically held in the second position when the energization of the said electromagnet is 40 above a predetermined minimum value, and the controlled member is operated away from the said second position by the operation of said second magnetic member due to the magnetic pull across the said second air 45 gap when the energization of the said electromagnet is above a predetermined maximum value.

2. An electric switch comprising a movable switch member biased to one position, a controlling electromagnet therefor having magnetic movable means for holding the said switch member in the second position, the said magnetic means being under the control of the magnetic pull across an air 50 gap in the flux path of the said electromagnet in the flux path of the said electromagnet when the energization of the said electromagnet is above a predetermined maximum value.

net when the said switch member is magnetically held in the second position, and a mechanical connection between the said magnetic means and the said switch member whereby the said switch member is directly operated away from the second position toward the first position by the movement of the said magnetic means to close the said air gap when the energization of the said electromagnet reaches a predetermined maximum value. 70

3. An electric switch comprising a switch member biased to one position, an electromagnet for magnetically holding the said switch member in a second position when 80 the energization of the said electromagnet is above a predetermined minimum value, the said electromagnet having a magnetic member biased to the unattracted position which moves to the attracted position under the control of the said electromagnet when the energization of the said electromagnet reaches a predetermined maximum value, and mechanical connections between the said magnetic member and the said 85 switch member whereby the said switch member is operated away from the said second position toward the first position by the said magnetic member when the energization of the said electromagnet reaches the 90 predetermined maximum value.

4. The combination in an electric switch of a switch member movable to and from a circuit opening and a circuit closing position, a magnet structure, movable magnetic 100 means mechanically connected to said switch member to move therewith to and from the said positions and disposed with respect to said magnet structure to provide an air gap which is closed by the closing of the switch and a second air gap which is open when the switch is closed, and a winding disposed on said structure for attracting the said movable magnetic means and thereby holding the said switch member in 105 the closed position when the first air gap is closed and the energization of the said winding is above a predetermined minimum value, and magnetically operating the said switch member to the open position by the pull of the said magnetic movable means across the said second air gap when the energization of the said electromagnet is 110 above a predetermined maximum value.

5. An electric switch comprising a movable switch member biased to one position, a controlling electromagnet therefor comprising a winding energized responsively to the current in the circuit controlled by the switch, and magnetic movable means for holding the said switch member in a second position, the said magnetic means being under the control of the magnetic pull across an air gap in the flux path of the said electromagnet when the energization of the said switch member is 120

125

130

magnetically held in the second position, and a mechanical connection between the said magnetic means and the said switch member whereby the said switch member is 5 directly returned to the first position by the movement of the said magnetic means to close the said air gap when the current in the said winding reaches a predetermined maximum value.

10 6. An electric switch, comprising a switch member biased to one position, an electromagnet having a winding energized responsively to the current in the circuit controlled by the switch for magnetically holding the 15 said switch member in a second position when the current in the said winding is above a predetermined minimum value, the said electromagnet having a magnetic member biased to the unattracted position which 20 moves to the attracted position under the control of the said winding when the current in the said winding reaches a predetermined maximum value, and a mechanical connection between the said magnetic member 25 and the said switch member whereby the said switch member is returned to the first position by the magnetic member when the current in the said winding reaches the predetermined maximum value.

30 7. A manually operable and automatic overload and under voltage protective switch, comprising a switch member biased to one position, an electromagnet having a winding energized responsively to the current through the switch for magnetically holding the said switch member in a second position when the current in the said winding is above a predetermined minimum value, the said electromagnet having 35 a magnetic member biased to the unattracted position which moves to the attracted position when the current in said winding reaches a predetermined maximum value, a mechanical connection between the 40 said magnetic member and the said switch member whereby the said switch member is returned to the first position by the magnetic member when the current in the said winding reaches the predetermined maximum value, and manually operable means 45 for mechanically moving the said switch member to the operated position and for mechanically returning the same to the first position.

50 8. The combination in a manually operable and automatic overload and voltage failure protective switch, of a switch member movable to and from a circuit opening and a circuit closing position, manually 55 operable push buttons for moving the said switch member to each of the said positions at will, a magnet structure, magnetic movable means mechanically connected to said switch member to move therewith to and from the said positions and disposed

with respect to the said magnet structure to provide an air gap which is closed by the closing of the switch and a second air gap which is open when the switch is closed, and a winding disposed on said structure 70 for attracting the said magnetic movable means and thereby holding the said switch member in a closed position when the first air gap is closed and the current in the said winding is above a predetermined minimum value, and magnetically operating the 75 said switch member to the open position by the pull on the said magnetic movable means across the second air gap when the current in the said winding is above a predetermined maximum value.

9. The combination in a push button switch, of a switch member, a push button for moving the switch to the circuit opening position and a push button for moving the same to the circuit closing position, a magnet structure, a magnetic movable member mechanically connected to the said switch member to be moved therewith upon operation of said push buttons and disposed with respect to the magnet structure to provide an air gap which is normally open and which is closed when the switch is in the closed position and a second air gap which is open when the switch is in the closed position, and a winding disposed on said magnet structure for attracting the said magnetic movable member whereby the switch member is magnetically held in the operated position when the first air gap is closed and magnetically returned from the operated position by the pull of the said magnetic movable member across the second air gap when the current in the 95 said winding is above a predetermined value.

10. The combination in an electric switch of a switch member biased to the open position, a controlling electromagnet therefor comprising a winding energized responsively to the current through the switch and two magnetic movable members controlled thereby for controlling the said switch member, and mechanical connections between the said switch member and the said movable magnetic members whereby the first of said magnetic members is mechanically moved into the magnetic field of said electromagnet independently of the other 110 upon the closing of the switch and the switch is magnetically held closed thereby while the current in the said winding is above a predetermined minimum value, and the said switch member is 115 moved to the open position by the magnetic attraction of the second magnetic member when the current in the said winding rises to a predetermined maximum value.

11. The combination in an electric switch 120 of a switch member biased to the open po-

- sition, a controlling electromagnet having two independently movable armatures controlled thereby for controlling the said switch member, the first of said armatures connected to the said switch member and the second of said armatures connected to the first armature and the said switch member, and means whereby the switch is closed by the independent operation of the second 65 armature and the said switch member is magnetically maintained in the closed position thereby when the energization of the said electromagnet is above a predetermined minimum value, and the said switch member is operated to the open position by the subsequent independent operation of the first armature when the energization of the said electromagnet is above a predetermined maximum value.
12. An electric switch comprising a switch member movable to and from an operated position, a controlling electromagnet therefor comprising a magnet structure and a winding energized responsively to the current through the switch for magnetically holding the switch member in the operated position when the current in the said winding is above a predetermined minimum value, a magnetic movable member connected to the switch member and disposed with respect to the said magnetic structure to provide an air gap, a second magnetic movable member cooperating therewith and disposed with respect to the said magnetic structure to provide a second air gap, and a resilient connection between the said magnetic members, whereby the switch member is moved to the operated position by the operation of one of said magnetic members to close its corresponding air gap and the switch member is returned to its original position by the operation of the second magnetic member due to the magnetic pull across the second air gap when the current in the said winding is above a maximum predetermined value.
13. An electric switch comprising a switch member movable to and from an operated position, a controlling electromagnet therefor comprising a magnet structure and a winding energized responsively to the current through the switch for magnetically holding the switch member in the operated position when the current in the said winding is above a predetermined minimum value, a magnetic movable member connected to the switch member, a second magnetic movable member, the said magnetic members disposed with respect to the said magnet structure to provide two air gaps in series, and a resilient connection between the said magnetic members, whereby the switch is closed by the closing of the air gap associated with the second magnetic member and the switch is opened by the closing of the air gap associated with the first magnetic member when the current in the said winding is above a predetermined value.
14. An electric switch comprising a switch member movable to and from an operated position, a controlling electromagnet therefor comprising a magnet structure and a winding energized responsively to the current through the switch for magnetically holding the switch in the operated position when the current in the said winding is above a predetermined minimum value, two magnetic movable members pivotally connected to each other and operatively connected to the said switch member, and a resilient connection between the said magnetic members for biasing the switch to the open position at which the magnetic members are disposed with respect to the said magnet structure to provide two air gaps in series, whereby the switch is closed by the air gap associated with one of the said magnetic members and the switch is opened by the closing of the gap associated with the other magnetic member when the current in the said winding is above a predetermined value.
15. The combination in a voltage failure and overload protective push button switch, of a switch member, a controlling electromagnet therefor having a single winding and two operatively connected magnetic movable members for controlling the said switch member, a push button cooperating with the first of said magnetic members for closing the switch and a push button cooperating with the second of said magnetic members for opening the same, and resilient means connecting the said magnetic members for biasing the said magnetic members and the said switch member to the open position, whereby the switch member is held in the closed position by the magnetic attraction of the electromagnet for the first of said magnetic members when the current in the said winding is above a predetermined minimum value and the switch member is returned to the open position by the magnetic attraction of the electromagnet for the second of said magnetic members when the current in the said winding is above a predetermined maximum value.
- In witness whereof, I have hereunto set my hand this 28th day of September, 1921.
- JOHN EATON.
